CLAIM

The ornamental design for a belt of a printing system, as shown and described.

DESCRIPTION

FIG. 1 is a top view of a first embodiment of a belt for a printing system showing the new design;

FIG. 2 is a bottom view thereof;

FIG. 3 is a right view thereof;

FIG. 4 is a left view thereof;

FIG. 5 is a front view thereof;

FIG. 6 is a back view thereof;

FIG. 7 is a perspective view thereof;

FIG. 8 is a top view of a second embodiment of a belt for a printing system showing the new design;

FIG. 9 is a bottom view thereof;

FIG. 10 is a right view thereof;

FIG. 11 is a left view thereof;

FIG. 12 is a front view thereof;

FIG. 13 is a back view thereof;

FIG. 14 is a perspective view thereof;

FIG. 15 is a top view of a third embodiment of a belt for a printing system showing the new design;

FIG. 16 is a bottom view thereof;

FIG. 17 is a right view thereof;

FIG. 18 is a left view thereof;

FIG. 19 is a front view thereof;

FIG. 20 is a back view thereof;

FIG. 21 is a perspective view thereof;

FIG. 22 is a top view of a fourth embodiment of a belt for a printing system showing the new design;

FIG. 23 is a bottom view thereof;

FIG. 24 is a right view thereof;

FIG. 25 is a left view thereof;

FIG. 26 is a front view thereof;

FIG. 27 is a back view thereof;

FIG. 28 is a perspective view thereof;

FIG. 29 is a top view of a fifth embodiment of a belt for a printing system showing the new design;

FIG. 30 is a bottom view thereof;

FIG. 31 is a right view thereof;

FIG. 32 is a left view thereof;

FIG. 33 is a front view thereof;

FIG. 34 is a back view thereof;
